Daniel Breed, Atty.

United States Patent Office.

JOHN F. FISHER, OF GREENCASTLE, PENNSYLVANIA, ASSIGNOR TO HIMSELF AND DANIEL BREED, OF WASHINGTON, DISTRICT OF COLUMBIA.

Letters Patent No. 101,990, dated April 19, 1870; antedated April 7, 1870.

IMPROVEMENT IN WHEAT-DRILLS.

The Schedule referred to in these Letters Patent and making part of the same.

To all whom it may concern:

Be it known that I, JOHN F. FISHER, of Green-
castle, in the county of Franklin and State of Pennsyl-
vania, have invented a new and useful Improvement
in Wheat-Drills; and I hereby declare the following
is a full description thereof.

In the accompanying drawings—

Figure 1 is a side view of a boot and drag-bar of a
wheat-drill, with my improvement attached.

Figure 2 is the same with the boot folded backward,
as if passing a stump or stone.

Figure 3 is a top view of my improvements.

My invention consists—

First, in a projection upon the ear of the boot, so
arranged as to form a set like a pocket-knife with the
check-link, and thus form a check to the check-link
itself, and also to the spring bar.

Second, it consists in a central check or set formed
between the check-link and ear of the boot.

Third in a check upon the spring bar itself, forming
a set with the check-link.

Fourth, in a loose guide-pin, or pin without a bur,
for holding the spring.

Fifth, in a loose washer upon the guide-pin; and

Sixth, in making the stirrup with a cap or cup to
receive the top of the spring.

In making my improved boot A, I cast the same
with projection B upon the ear of the boot.

This projection extends forward to about the mid-
dle of the check-link C, and is wide enough to bear
nearly or quite the whole width of the top of said
link, as shown in fig. 3.

The center of the link may also be made to have a
set with the central part of the ear, the bearing being
upon the point c, fig. 3.

Upon the spring bar D I place a check, E, which
has a set with the link C, as shown in fig. 1, at e.

The guide-pin I is made separate from the washer
H, for the convenience in casting the same, it being
much more difficult to draw the mold when the guide-
pin and washer are cast together or in one piece.

The stirrup G is cast with a cup or cap to receive
the top of the spring. This is an improvement upon
having a separate cap or washer above the spring,
where it is sometimes liable to get out of place.

By this construction considerable time is saved in
fitting up the parts near the spring, neither the guide-
pin, washers, or stirrup requiring any finishing what-
ever, bur, or screw.

Having described my invention,

I claim—

1. The projection B upon the ear of the boot, or its
equivalent, substantially as set forth.
2. The central set between the check-link C and
the ear of the boot, substantially as described.
3. The check E, or its equivalent, on the spring
bar, having a set with the check-link, substantially as
specified.
4. The loose guide-pin I, or pin without a bur, sub-
stantially as set forth.
5. The loose washer H, made separate from the
guide-pin I, substantially as set forth.
6. Stirrup G, when provided with a cap or cup to
receive the top of the spring, substantially as set forth.

JOHN F. FISHER.
